WALDEMAR DYRSSEN, OF NEW YORK, N. Y.

ELECTRODE-FURNACE.

1,317,911.

Specification of Letters Patent.

Patented Oct. 7, 1919.

Application filed December 21, 1918. Serial No. 267,787.

To all whom it may concern:

Be it known that I, WALDEMAR DYRSSEN, a subject of the King of Sweden, residing in the city, county, and State of New York, have invented certain new and useful Improvements in Electrode-Furnaces, of which the following is a specification.

The invention aims to provide an improved method of supporting or counterbalancing the electrodes of electrode furnaces. It is particularly designed for electric arc furnaces with vertical electrodes passing through the roof. These electrodes are generally separately movable by means of electric motors. The electrodes are quite heavy, especially for the larger furnaces, and their weight is increased by the holder and the electric cables therefrom to the transformer or other source of current.

20 The accompanying drawings illustrate embodiments of the invention applied to electric furnaces of the Heroult arc type carrying three electrodes which have to be separately adjusted.

25 Figure 1 is a vertical section, Fig. 2 a plan and Fig. 3 a partial horizontal section. of a furnace of large size;

Fig. 4 is a side elevation and Fig. 5 a vertical section of a furnace of smaller size.

30 The furnace A has a roof B through which pass the three vertical electrodes C, D and E. Each of these is carried by a holder F extending transversely across the top of the furnace and connected by a cable G to the transformer. In practice the holder F is raised and lowered, carrying with it the electrode and the near end of the looped cable.

35 The movable parts are supported from an overhead platform H which is carried by columns J K fixed on the sides of the furnace, so that when the furnace is tilted the electrode-supporting structure moves with it.

The holder F of the electrode D is suspended at two points so as to maintain it horizontal by means of cables L and M, the first passing over a fixed guide pulley N and both passing over a fixed double guide pulley O and fastened to a block R which slides on guides Q on the top of the platform. The 45 holders for the other electrodes are similarly supported by cables L and M extending to blocks P and S, all the blocks being arranged to slide on parallel guides. Each block is connected to a rod T which is threaded through a worm wheel U driven by a worm on the shaft of a motor V; each

motor being operated independently of the others as it becomes necessary to raise or lower its electrode. Each of the blocks carries a horizontal pulley. A cable W is 60 looped back and forth between these pulley blocks and horizontal pulleys X mounted between them, and the ends of the cable W are passed over vertical pulleys Y above the side of the furnace and carry counterweights 65 Z which are guided on the columns K.

Each unit comprising an electrode and its holder and related parts is supported by a loop of the cable W so that the strain on the cable is equal to one-half of the weight 70 of the unit supported. Therefore, the weight on each vertical end of the cable W is half the weight of an electrode with its connected parts. The counterweights Z, therefore, are made each approximately half the weight 75 of the electrode and connected parts. If the weight of each electrode and holder is the same, they are all in perfect balance and there are no stresses in the operating rods T for the several blocks P R and S. In practice the weights are approximately the same. The several electrodes counterbalance one another, and the weights Z constitute a common counterbalancing means for the several electrodes. When one of the blocks is moved 80 by its motor the two counterweights, supposing them to move equal distances, move the same distance as the block and the electrode carried thereby. The weight of one electrode is used to counterbalance in whole or 85 in part the weight of another. But it will be understood that in practice the actual movement of an electrode will be transmitted through the common cable to the end or ends of the latter and there will be no necessary movement of the other electrodes.

Comparing this system with the use of independent counterweights for the several electrodes, each of which must be of the same weight as its electrode and holder, the 100 total of the three counterweights would be three times as great as that of the counterweights Z required by the present invention.

The two counterweights Z are in line with the sides of the platform and there is no 105 intermediate counterweighting mechanism below the platform; so that we have a large free opening under the platform and between the two columns K through which to pass the holders and electric cables. This 110 is important in keeping down electrical losses and heating effects on the surrounding

steel work of columns and platform; such losses being substantial where the surrounding steel work has left only small openings for the passage of the electrical connections carrying a current of large volume.

The small size of the counterweights which can be used by the present arrangement makes it possible to use also an overhead platform and supports which are comparatively light and the saving thus effected is considerable, especially for furnaces of the larger sizes.

For smaller furnaces the motors and lifting mechanism may be arranged in a vertical position on the side of the furnace, and such an arrangement is shown in Figs. 4 and 5. Here motors V and worms U are mounted on a small platform H supported by brackets on the side of the furnace and the rods T are vertical and connected at their upper ends to blocks P' R' and S'. Each electrode holder F has a cable M supporting its forward end and running over vertical pulleys 2 and 3 and down to the corresponding block 25 P' R' or S'; and a cable L runs from the rear end of each holder upward and over a guide pulley 4 and thence down to the same block as the cable M of the holder in question. The bight or loop of the counterbalancing cable W between the blocks P' R' and S' passes over pulleys X' which are mounted on the side of the furnace, the ends of the counter-balancing cable passing over the upper and lower guide pulleys Y' and Y² as 30 the most convenient arrangement and carrying counterweights Z' each of which is about half as heavy as one of the electrodes with its connected parts. This system is in balance the same as that described in connection 35 with Figs. 1, 2 and 3.

Various modifications are possible in the arrangement of the counterweights without departing from the principle that the electrodes are so connected as to partly or fully 40 counterbalance one another. It is possible to discard one of the separate counterweights Z or Z', allowing the other to travel twice the distance through which an electrode is moved. The principle can be applied not only to furnaces of the type shown but to other furnaces where adjusting of the electrodes is required; and it can be used also for a furnace having two electrodes or having more than three. It is not essential that the 45 weights of the electrodes be exactly counterbalanced. They may be over balanced or under balanced. In fact, in practice as the electrodes burn away or are added to their weight will vary though the variation will 50 not be great enough to cause undue strain on the adjusting mechanism. Various equivalents of pulleys and cables are known by which the downward pull of one electrode may be transmitted to another electrode or a 55 counterweight in an upward direction, and

such equivalents may be used in place of the cable and pulleys illustrated.

The motor-operated threaded rods T and their connections serve for independently adjusting the electrodes and holding them; the counterbalancing means serving to reduce the strains on them to a minimum, approximately zero in normal operation. When any one of the electrodes burns away so that its arc becomes too long its motor and controlling rod T are actuated, usually by automatic mechanism, to feed it down. In this operation the other two electrodes remain unmoved, their pulley blocks being stationary and the counterweights Z alone 70 moving. And in case any large part of one of the electrodes breaks off, the adjustment of the other two will also remain undisturbed while the broken electrode is being restored to working condition.

The common method of supporting such electrodes has been by means of a cable and an electrically operated winch which pulls on the cable or pays it out to raise or lower the electrode. The same adjusting means may be applied with the present counterweighting system. For example, instead of the threaded rods T of Fig. 4 cables may be attached to the blocks P' R' and S', running down to motor-operated winches. Such cables will hold these blocks and their electrodes against the weight of the latter. But the counterweights Z' in this case cannot be made heavy enough to counterbalance an entire unit consisting of electrode and holder 80 and connected parts; because in that case the breaking off of a large piece of the electrode or the slipping of an electrode through its holder would lessen the downward pull on the latter and the weights Z' would pull 85 down the block (P' R' or S') which supported the holder, the movement continuing to the limit of permissible movement of the weights Z'. To avoid this the total of these 90 weights had better be made just sufficient to balance or slightly overbalance the weight of a holder and connected parts exclusive of the electrode. This is generally the greater part of the total weight of the unit and its counterbalancing is a matter of considerable 95 value. I have spoken of the counterbalancing of the electrode but it will be understood that I include in this term the counterbalancing in whole or in large part of the unit comprising the electrode and its holder and 100 connected movable parts.

Various other modifications of the mechanism shown may be made by those skilled in the art and parts of the mechanism shown may be used separately from other parts 105 without departing from the invention as described in the following claims.

What I claim is:

1. An electrode furnace having a plurality of electrodes, one counterbalancing another. 110

2. An electrode furnace having at least three electrodes connected together in a common counterbalanced system.
3. An electrode furnace having a plurality of electrodes, one counterbalancing another in combination with separate counterbalancing means.
4. An electrode furnace having a plurality of electrodes, a pulley and a cable supporting the weights of said electrodes and passing from one electrode over said pulley to another so as to balance one electrode against another.
5. An electrode furnace having at least three electrodes, pulleys and a single cable supporting the weights of said electrodes and passing from each electrode over a pulley to another electrode so as to balance the electrodes against one another.
6. An electrode furnace having a plurality of adjustable units each comprising an electrode and holder and related parts, one of said units counterbalancing another.
7. An electrode furnace having a plurality of vertical electrodes, an overhead supporting structure and means carried thereby for transmitting the downward pull of one electrode as an upward pull on another.
8. An electrode furnace having vertical electrodes each with a holder extending across the top of the furnace, cables supporting each holder at two points to maintain it parallel, a block for each holder to which the upper ends of said cables are attached and a cable connecting said blocks and passing over an intermediate pulley.
9. An electrode furnace having a plurality of electrodes and a common counterbalancing means for said electrodes.
10. An electrode furnace having a plurality of electrodes, a common counterbalancing means for said electrodes, and means for positively adjusting and holding said electrodes.
11. An electrode furnace having a plurality of electrodes, one counterbalancing another, and independent means for adjusting and holding each of said electrodes.
12. An electric furnace having a plurality of electrodes, electric connections to said electrodes and counterweighting means for the electrodes arranged outside of the space through which the several connections pass.

In witness whereof, I have hereunto set my hand.

WALDEMAR DYRSSEN.
